UNITED STATES PATENT OFFICE.

ERNEST H. WAKEFIELD, OF VERMILION, OHIO.

HANGER FOR LIGHTING-FIXTURES.

961,050.

Specification of Letters Patent.

Patented June 7, 1910.

Application filed November 6, 1909. Serial No. 526,622.

To all whom it may concern:

Be it known that I, ERNEST H. WAKEFIELD, a citizen of the United States, residing at Vermilion, in the county of Erie and 5 State of Ohio, have invented new and useful Improvements in Hangers for Lighting Fixtures, of which the following is a specification.

The present invention provides suspending means for electroliers and lighting fixtures generally of the chandelier type adapted to hang pendent from a ceiling or overhead support, the purpose being to provide a hanger which will admit of the fixture being readily placed in position and adapted to automatically adjust itself so as to hang perpendicularly.

The invention provides suspending means for hanging fixtures which are designed to 20 be removed and replaced and which are not coupled to service pipes in contradistinction to features of the type utilizing gas as the illuminating medium and which fixtures are connected to the service pipe by screw thread 25 joints.

The present invention overcomes the difficulties incident to attaching electroliers to the ceiling, the general practice being to attach the fixture by means of screws let 30 into the ceiling and it being necessary to support the fixture during the hanging operation. One of the chief objections to this practice is the difficulty experienced in supporting the weight of the fixture and 35 at the same time driving the attaching screws home. Another objection resides in the fact that plastering drops and is liable to cause inconvenience and pain to the workmen by getting in the eyes and is further objectionable in dropping upon projecting 40 parts of the fixture. Another serious objection resides in the fact that unless the part of the ceiling to which the fixture is attached is perfectly level the fixture will 45 not hang perpendicularly and it is necessary to bend or strain the parts in order to plumb the same.

The objectionable features herein noted are overcome by the present invention, 50 which resides in the novel features and details of construction which hereinafter will be more particularly set forth, pointed out in the claim and illustrated in the drawings hereto attached, in which,

55 Figure 1 is a side view of the upper portion of a fixture suspended by means em-

bodying the invention, parts of the hanger being broken away. Fig. 2 is a vertical central section of the parts illustrated in Fig. 1. Fig. 3 is a view of the hanger as seen 60 from below. Fig. 4 is a side view of the connector.

Corresponding and like parts are referred to in the following description, and indicated in all the views of the drawings, by 65 the same reference characters.

The invention comprises essentially two parts, a hanger A and a connector B. The hanger A comprises a socket 1 and basal flanges 2, the latter being apertured, as indicated at 3, to receive screws 4 or like fastenings. The socket 1 is pressed from the plane of the basal flanges 2 and tapers and is provided at its lower end with an opening 5, which receives the connector B. A side 70 portion of the socket 1 is cut away, as shown at 6, to form an unobstructed passageway for the ingress and egress of the connector B. The edge portions of the socket upon the opposite sides of the passageway 6 are outwardly flared, as indicated at 7, to assist in 75 directing the connector into the socket when placing the fixture in position.

While the hanger may be formed in any manner it is observed that the construction 85 is such as to admit of its being struck from sheet metal, the socket, flanges and openings 3 in the flanges being formed at one operation when striking the hanger from a blank or piece of sheet metal of proper gage. It 90 will thus be understood that the hanger may be cheaply manufactured and embodies a minimum amount of material in construction and is therefore light and capable of being finished in an artistic manner. When 95 in position the socket is prevented from spreading by the fastenings 4 passing through the openings 3.

The connector B comprises a cylindrical body 8, outer shoulders 9 and 10 and a projecting portion 11. The shoulder 9 tapers to conform approximately to the taper of the socket 1 so as to sustain the weight of the fixture and to admit of the latter adapting itself so as to hang perpendicularly. 100 The shoulder 10 limits the upward movement of the connector when placing the same in position. The projecting part 11 enters the casing 12 of the fixture and serves to centralize the same, the pipe 13 forming the 105 main stem of the fixture is threaded into the lower end of the connector B and may be 110

passed through said connector if necessary to effect any desired result. The bore or opening 14 of the connector is slightly enlarged at its upper end, thereby admitting 5 of the upper portion of the pipe 13 passing therethrough.

To use the invention so as to obtain the advantages thereof the hanger A is placed in position upon the ceiling and fastened 10 thereto by means of the screws 4. The upper end of the stem of the fixture is provided with the connector B, which is threaded upon the pipe 13 and has the projecting portion 11 entering the casing 12. The fixture 15 is placed in position by slipping the cylindrical portion 8 of the connector through the passageway 6 into the opening 5, after which the fixture is lowered until the shoulder 9 engages the lower end of the socket 1 when 20 the hanging is completed. The construction is such as to admit of the fixture adapting itself automatically so as to hang in a vertical line.

From the foregoing description, taken in 25 connection with the accompanying drawing, the advantages of the construction and of the method of operation will be readily apparent to those skilled in the art to which the invention appertains, and while I have 30 described the principle of operation of the invention, together with the device which I now consider to be the embodiment thereof, I desire to have it understood that the device shown is merely illustrative, and that such

changes may be made when desired as are 35 within the scope of the claim appended hereto.

Having thus described the invention what is claimed as new, is:—

Suspending means for electroliers and like 40 lighting fixtures, the same comprising a hanger and a connector, the hanger comprising a tapered socket portion having oppositely disposed basal flanges formed in their ends with openings, said socket having a 45 portion at one side cut away to provide a passageway and having the edge portions of the socket upon opposite sides of the passageway flared, and a connector comprising a cylindrical body having spaced shoulders 50 extending outwardly, the upper shoulder being tapered and said connector also having a projecting portion to enter the casing of the fixture and centralize the same, the opening of the connector being enlarged at its upper 55 end and having its lower portion internally threaded to make screw thread connection with the stem or pipe of the fixture, said connector having free ingress and egress through the passageway of the hanger leading into the socket thereof.

In testimony whereof I affix my signature in presence of two witnesses.

ERNEST H. WAKEFIELD.
